No. 818,701.

PATENTED APR. 24, 1906.

W. E. MOULTON,
FASTENING DEVICE FOR UMBRELLA HANDLES.

APPLICATION FILED MAY 19, 1905.

UNITED STATES PATENT OFFICE.

WALTER E. MOULTON, OF PLAIN CITY, OHIO.

FASTENING DEVICE FOR UMBRELLA-HANDLES.

No. 818,701.

Specification of Letters Patent.

Patented April 24, 1906.

Application filed May 19, 1905. Serial No. 261,115.

To all whom it may concern:

Be it known that I, WALTER E. MOULTON, a citizen of the United States, residing at Plain City, in the county of Madison and 5 State of Ohio, have invented certain new and useful Improvements in Fastening Devices for Umbrella-Handles, of which the following is a specification.

My present invention pertains to improvements in fastening devices for umbrella-handles, the construction and advantages of which will be hereinafter set forth, reference being had to the accompanying drawings, wherein—

15 Figure 1 is a side elevation of a portion of an umbrella staff, handle, and attaching means, portions being shown in section to more clearly illustrate the invention; Fig. 2, a similar view at right angles to that shown 20 in Fig. 1; Fig. 3, a transverse horizontal sectional view on the line 3 3 of Fig. 1; Fig. 4, a perspective view of the lower portion of the staff; Fig. 5, a similar view, the parts being shown in a slightly different position; and 25 Fig. 6, a perspective view, partly in section, of the retaining-sleeve or socket-piece.

The object of the present invention is to provide a simple and efficient lock for detachable umbrella-handles. As is well known, 30 the cost of making a detachable handle is quite an item in the manufacture of umbrellas, and this invention provides a simple and inexpensive construction which nevertheless is highly efficient in operation.

35 In the drawings, A designates the handle, which is bored out at its upper end to receive a tubular member or socket-piece B, which is forced down into the handle, said socket-piece being provided at its upper end with a vertically-disposed slot or recess C. It is also provided with a locking pin or wire D, (best seen upon reference to Figs. 3 and 6,) which is placed to one side of the center of the socket-piece.

40 E denotes the staff, which, as shown in the drawings, is preferably of tubular form. The lower end thereof is cut away to one side of the center, a laterally-extending slot or recess F being formed in the staff at the upper end 45 of the reduced portion. The cutting away of the staff and the formation of the slot is a comparatively simple operation. The lower end of the staff may thus be formed or shaped by two operations—first, a cut of the saw ex-

tending lengthwise or longitudinally of the staff, and, second, a cut extending transversely of the staff, or the operations may be reversed.

50 The cut-away portion at the lower end of the staff stands out of alinement with the spring-pressed retaining latch or member G, the lower end of which when the parts are properly positioned extends into the recess C, formed in the upper end of the tubular member or socket-piece. Said spring-pressed 55 latch stands in alinement with the slot F, so that when the staff is passed down into the socket-piece the cut-away portion permits the lower end of the staff to pass beyond the cross-wire D. Upon rotation of the staff, 60 when the parts are thus positioned, the wire passes into the slot F, the latch G at the same time entering the recess C. Wire D prevents longitudinal movement of the handle with 65 reference to the socket-piece, and the latch 70 G prevents relative rotation of the parts.

The construction, as will be noted, forms a simple and efficient locking device for the handle and staff. By placing the wire D to one side of the center of the tubular member 80 B there is less danger of the same becoming bent. Furthermore, a shorter piece of wire may be employed than if it extended diametrically across the tubular member. Again, in view of the fact that the locking-wire D is 85 located to one side of the center of the member B it is necessary to cut away but a small portion of the lower end of the staff, and said end is not thereby materially weakened.

As socket-pieces and staffs are made of 90 standard size, the handles may be readily shifted from one umbrella to another or a new handle attached whenever this may become desirable.

Having thus described my invention, what 95 I claim is—

In combination with an umbrella-handle, a tubular member or socket-piece mounted therein, said member being provided with a vertically-disposed slot in its upper end; a 100 locking-pin secured in the tubular member, said pin standing to one side of the center of said member; a tubular staff having a section of less than half its diameter removed from the lower end and provided also with a slot F 105 extending laterally from the cut-away portion; and a spring retaining device carried by the staff, said device standing in alinement

2
with the slot F in the lower end of the staff, whereby when the parts are properly positioned the pin will pass into slot F, the retaining device will enter the slot in the upper 5 end of the tubular member, and the parts be held against relative rotation and longitudinal separation.

In testimony whereof I have signed my name to this specification in the presence of two subscribing witnesses.

WALTER E. MOULTON.
